UNITED STATES PATENT OFFICE.

JOHN W. HOWELL, OF NEWARK, NEW JERSEY, ASSIGNOR TO GENERAL ELECTRIC COMPANY, A CORPORATION OF NEW YORK.

MACHINE FOR TREATING FILAMENTS.

1,010,914.

Specification of Letters Patent.

Patented Dec. 5, 1911.

Application filed October 17, 1903, Serial No. 177,434. Renewed April 3, 1908. Serial No. 424,931.

To all whom it may concern:

Be it known that I, JOHN W. HOWELL, a citizen of the United States, residing at Newark, county of Essex, State of New Jersey, have invented certain new and useful Improvements in Machines for Treating Filaments, of which the following is a specification.

This invention relates to machines for treating filaments for incandescent lamps by 10 depositing graphitic carbon upon the filament to give it the desired resistance and make the resistance uniform at all points along its length. For this purpose the filament is supported in an air-tight receptacle or bottle with its ends held in metallic clips by which it is connected in an electric circuit and when the air has been withdrawn from the receptacle, a hydrocarbon or other 15 carbonaceous vapor is admitted and the filament is brought up to incandescence. The carbon in the vapor is thus precipitated on the surface of the filament, building it up and increasing its current carrying capacity 20 at all points but more rapidly at the weaker points which being of greater resistance are brought to a higher temperature by the current and thus precipitate more of the carbon. In this way the filament is built up 25 until its resistance is practically uniform throughout its length and then, as the deposition of the carbon continues, the resistance of the filament is steadily and uniformly decreased. In the machines which have been 30 constructed heretofore for treating filaments in this manner, the valves for connecting and disconnecting the pumps by which the treating bottles are exhausted of air, and the valves by which the treating bottles are con- 35 nected with and disconnected from the source of hydrocarbon vapor supply, have been operated manually. Operating all of the 40 valves and switches for each filament consumes a large portion of the operator's time 45 and materially limits the number of filaments that can be treated in a given time on the machine. In addition to this, the conditions, in the bottle, as to vacuum and hydro- 50 carbon vapor being determined by the operator for each filament and being dependent upon the faithfulness and skill of the operator, are apt to vary considerably.

One object of this invention is to provide a machine in which the circuit connections 55 and the connections between the treating

bottle and the pump and vapor supply are made and broken automatically. The treating bottle is therefore properly connected to the pump, and is connected to the vapor supply the same length of time in every case, 60 giving the same conditions of vacuum and vapor density for each filament and thus making the treated filaments far more uniform. Moreover the operator is relieved of numerous duties so that a much greater number of filaments can be treated in a given time. 65

The presence of a supply of hydrocarbon fluid on the filament treating machines used prior to this invention has always been an 70 element of danger.

Another object of this invention is to reduce this danger to a minimum. This is done by providing a supply apparatus, distant from the treating machine and care- 75 fully protected, in which the hydrocarbon is stored and from which it is drawn as needed into the treating bottle or bottles of one or any number of machines. Means are also provided for insuring a uniform charge of 80 vapor being admitted to each of the treating bottles each time. After the bottle has been exhausted of air, the automatically-operated valves disconnect it from the pumps and connect it directly with the vapor supply tank through a small opening of definite size. As the pressure of the vapor is main- 85 tained constant and as the length of time that the bottle is connected to the supply tank is the same in every case, the charge of 90 vapor which passes into the treating bottle, on which the quality of the work depends largely, is always the same. In the preferred form of the invention, however, a measure is employed for measuring out the charge or 95 dose of vapor which is admitted to the treating bottle instead of depending on the time elapsing between the opening and closing of the valves for uniformity of the charge. With this construction a vessel of definite 100 size, usually termed a "doser", is inter- posed between the supply tank and the treating bottles and is connected by valves with one and then the other alternately. As the bottles are exhausted of air prior to being 105 connected to the doser, the vacuum draws the vapor out of the doser and into the bottle, leaving the doser exhausted so that when it is connected to the supply tank, the 110 vacuum helps to fill it with the vapor. Thus

the vapor is actually measured out and the measure full, a definite amount, put in the treating bottle each time.

My invention therefore comprises a filament treating machine in which hydrocarbon vapor for the treating is drawn from a supply reservoir distant from the machine; it also comprises a treating machine in which a uniform charge of vapor is admitted to the treating receptacle each time; it also comprises a treating machine in which these charges are obtained by filling a measure of definite size and using the vapor thus measured out in the treating receptacle; it also comprises a treating machine having valves arranged to connect a measure or doser with a source of fluid supply and with a treating receptacle alternately; it also comprises a machine having one or more receptacles in which filaments are treated, and automatically-operated valves for connecting the receptacles to and disconnecting them from an air pump; a treating machine having automatic valves for connecting the treating receptacles with and disconnecting them from a source of fluid supply; a treating machine having automatic switches for cutting the filaments into and out of circuit.

30 The invention further comprises other novel features which will be described more in detail hereinafter and which will be definitely indicated in the appended claims.

In the accompanying drawings, which illustrate one embodiment of my invention, Figure 1 is an elevation of the operating mechanism of the machine; Fig. 2 is a top plan view of the same, broken away in part; Fig. 3 is a top plan view of the seat of one of the valves; Fig. 4 is a bottom plan view of the movable member of that valve; Figs. 5 and 6 are similar views of the seat and movable member of the second valve; Fig. 7 is a detail view of the operating gears; Fig. 8 is a detail view of the circuit-closer; Fig. 9 is a diagrammatic view showing the connections established by the valves between the treating bottles and the various other parts; and Fig. 10 is a diagrammatic view of the electrical connections.

The machine consists of a table on which are mounted the treating bottles, switches and other parts which must be accessible to the operator. In the top 5 of the table are a number of openings in each of which is located one of the treating bottles 1, 2, 3 and 4, as shown in Fig. 9. In the drawings, four of these treating bottles are shown and that is the number which I prefer to use, 55 but it must be understood that a greater or less number may be used instead. Each of the bottles is air-tight, except for an opening in the bottom into which a pipe is fitted and an opening in the top which is arranged 60 to be closed by a cap 6 carrying on its under

side a pair of metallic clips 7, 7 which hold the filament while it is undergoing treatment and by which the filament is connected in circuit. The clips 7, 7 connect through the cap with two metallic strips 8, 8 insulated from each other and adapted to make contact when the cap is placed in position with two other strips 9, 9 provided with binding-posts as shown diagrammatically in Fig. 10.

Beneath the treating bottles is mounted the operating mechanism shown in Figs. 1 to 8 inclusive. This consists of a shaft 10 mounted in bearings 11, 11 on a suitable base and carrying a member 12 having an opening therein parallel to its axis, in which a spring-pressed pin 13 having a head 14 is adapted to slide. Loosely mounted on the shaft 10 is a sleeve 15 carrying a wheel 16 close to member 12 on shaft 10 and a gear 17 and driven continuously from any suitable source of power by a chain running on the gear 17. The wheel 16 is provided with a number of openings in the side adjacent member 12 into one of which the end of pin 13 is adapted to slide to lock member 12 in engagement with wheel 16 and cause shaft 10 to rotate with sleeve 15. Mounted in proximity to these parts is an electromagnet 18 having an armature 19 carried by an arm 20 rigidly secured to a shaft 21 mounted in suitable bearings. Rigidly secured to shaft 21 is a finger 22 which extends into engagement with the head 14 of the clutch pin 13 and governs the engagement of pin 13 with wheel 16. For this purpose finger 22 is provided with an inclined side on which the head 14 of the clutch pin rides and by which the pin is drawn from engagement with wheel 16 against the tension of its spring. Armature 19 is retracted by a spring 23 having one end secured eccentrically to shaft 21 and the other end secured to the base at any convenient point. Rigidly mounted on shaft 21 is an arm 24 having a screw 25 in its outer end adapted to abut against the bearing 11 or any other stationary part of the device to limit the movement of shaft 21 and the parts carried thereby when retracted by spring 23 and to render the movement adjustable. Secured to the end of shaft 10 is an arm 26 to the end of which the rod 27 is pivotally connected for a purpose to be hereinafter described.

Rigidly mounted on shaft 10 is a two-toothed gear-wheel 28 co-operating with an eight-toothed wheel 29 rigidly mounted on a shaft 30, the two wheels forming a gear of the Geneva type, the arrangement being such that wheel 29 makes one quarter of a revolution for each full revolution of wheel 28 in two steps of one-eighth of a revolution each, between which steps gear 29 is locked against movement. Thus when magnet 18 is energized armature 19 is attracted, shaft 120

21 rocked, and the end of finger 22 raised until the head 14 of the clutch pin is freed. Clutch pin 13 is then pressed forward by its spring until the end of the pin extends 5 into one of the openings in wheel 16, locking members 12 and 16 together so that shaft 10 turns with sleeve 15 in a direction to cause the head 14 of the clutch pin to move away from shaft 21. If the circuit through magnet 18 is immediately broken, the free end 10 of finger 22 drops to its original position and when shaft 10 has made almost a complete revolution the head 14 of the pin abuts against and rides up the incline on the side 15 of finger 22, withdrawing pin 13 from engagement with wheel 16 and bringing shaft 10 to rest when it has made one complete revolution. During this movement shaft 30 and the parts carried thereby make one-quarter of a revolution in two steps of one-eighth of a revolution each, the shaft being 20 locked against movement after each step. Gear 28 is so positioned on shaft 10 that when the head 14 of the clutch pin is held 25 by finger 22, one of the teeth of the gear-wheel is close to the position in which it engages the teeth of gear 29.

The shaft 30 is mounted in bearings 31 31 and carries the movable member 32 of a circuit-closer and the movable members 33 and 34 of two disk valves. The circuit-closer is a contact 32 carried by an arm secured to shaft 30 and adapted to bridge one of four pairs of contacts 35, 36, 37 and 38 secured 35 to a standard 39 and symmetrically disposed about its center as shown in Fig. 8, the standard being mounted on the base perpendicular to shaft 30 with the shaft extending through a central opening therein. The 40 arm carrying the contact 32 is so positioned on shaft 30 that when the shaft comes to rest after each quarter of a revolution, contact 32 is bridging one of the pairs of stationary contacts.

45 On one end, the shaft 30 carries the movable member 33, shown in Fig. 4, of one of the two disk valves which govern the admission of air and vapor to and its exhaustion from the treating bottles and the 50 charging of the doser. The disk 33 cooperates with a valve seat 40, shown in Fig. 3, mounted on the base, the two abutting surfaces being accurately finished to prevent leakage. At the other end of shaft 55 30 is a similar arrangement of parts constituting the second valve, the movable member 34, shown in Fig. 6, being mounted on the end of shaft 30 and co-operating with the seat 41, shown in Fig. 5, mounted on 60 the base. Each of the valve seats 40 and 41 is provided with four ports symmetrically disposed about its center as indicated at 42, 43, 44 and 45 on seat 40, and 46, 47, 48 and 49 on seat 41. Connected to the 65 four ports of seat 40 are four pipes which

lead outward and then upward and are connected each to the end of one of the pipes 50, 51, 52 and 53 which extend along under the treating bottles 1, 2, 3 and 4 and are connected each to one of the bottles by a 70 pipe entering the bottom of the bottle. Connected to the four ports of valve seat 41 are four similar pipes which connect with the other ends of pipes 50, 51, 52 and 53 as shown diagrammatically in Fig. 9. In the 75 preferred form of the invention, two pumps are used for exhausting the treating bottles, one for rough, preliminary exhaustion and the other for perfecting the vacuum. Each of the valve seats 40 and 41 has a central port 54 and 55 respectively to which pipes 56 and 57 respectively are connected, the former connecting the fine pump 58 to the central port 54 of the first valve and the latter connecting the rough pump 59 to the 80 central port 55 of the second valve. The valve seat 40 is also provided with four ports 60, 61, 62 and 63 equi-distant from the center and lying adjacent to the ports 42, 43, 44 and 45 as shown. From these 85 four ports pipes lead to a common connection from which a pipe 64 leads to the doser 65, a vessel of sufficient size to hold a single charge of vapor for one of the 90 treating bottles and located in any convenient position under the operating table. The seat 40 is also provided with a port 66 farther from the center than the other ports, from which a pipe 67 leads to a tank 68 distant from the machine in which the hydrocarbon vapor is maintained at a constant 95 pressure. Extending up through the base to the bottom of valve seat 40 is a steam pipe 98 by which the valve seat is kept hot to prevent condensation of the vapor. The 100 valve seat 41 is provided with a port 69 at a greater distance from the center than ports 46, 47, 48, 49, to which is connected a pipe 70 open at its other end and serving as an air connection for the treating bottles. 110 The movable member 33 of the first valve is provided with a passageway 71 adapted to cross-connect the central port 54 leading to the fine pump with one of the ports 42, 43, 44, 45 leading to the treating bottles. 115 This passageway is sector-shaped and is so positioned that when shaft 30 and the movable member make one quarter of a revolution in two steps, connection with one of the ports is broken and connection established 120 with the next port at the beginning of the first step, which connection is maintained during the second step and the pause at the end of the movement. The movable member is also provided with a passageway 125 72 adapted to cross-connect one of the ports leading to the treating bottles with that port of the series 60, 61, 62, 63 leading to the doser which lies adjacent thereto. This passageway is so shaped and positioned that 130

it connects with the doser the treating bottle which has just been disconnected from the fine pump at the end of the first step of the quarter revolution and maintains this connection only during the pause between the two steps. The movable member is also provided with an annular passageway 73 co-operating with the port 66 leading to the vapor supply tank in all positions of the movable member. Passageway 73 is provided with a small offset passageway 74 which, with the passageway 73, cross-connects one of the ports 60, 61, 62, 63 leading to the doser with port 66 and the vapor supply tank at the end of each quarter revolution. The movable member 34 of the second valve is provided with a passageway 75 adapted to cross-connect the central port 55 leading to the rough pump with one of the ports 46, 47, 48, 49 leading to the treating bottles. This passageway is also sector-shaped and is so positioned that in each quarter revolution connection is broken with one of the ports and connection established with the next port at the beginning of the first step, which connection is maintained during the second step and the pause at the end of the movement. Movable member 34 is also provided with an annular passageway 76, co-operating with the port 69 of the air pipe in all positions of the movable member. Passageway 76 is provided with a wide offset passageway 77 adapted to cross-connect the port of the series 46, 47, 48, 49 in advance of the one connected to the rough pump with passageway 76, port 69 and air pipe 70 at the end of the first step of the quarter revolution and maintain this connection during the second step and the pause at the end of the movement. The movable members 33 and 34 are so positioned on shaft 30 relatively to one another that member 34 of the second valve connects with the rough pump the bottle in advance of the one connected to the fine pump by member 33 of the first valve and the same movement which disconnects the rough pump from a bottle connects the fine pump to that bottle.

50 The successive connections established by the valves can be best understood by reference to Fig. 9, which shows the various parts, except the electrical connections, diagrammatically, with the movable members of the valves in the position they occupy during the pause following one of the quarter revolutions, the arrows indicating the direction of movement of the movable members 33 and 34. In this position, bottle 1 is open to the air through pipe 53, port 49, passages 77 and 76, port 69 and pipe 70, and the operator may withdraw cap 6, remove the treated filament, insert a filament to be treated in the clips 77 and return cap 6 to the closed position; bottle 2 has been evacuated and

charged with a dose of hydrocarbon vapor and the filament connected in circuit, so the pipe 52 connected to this bottle is closed at the valves; bottle 3 is connected to the fine pump 58 through pipe 51, port 43, passage 74, port 54 and pipe 56, the outer end of pipe 51 being closed at port 47; bottle 4 is connected to the rough pump 59 through pipe 50, port 46, passage 75, port 55 and pipe 57, the other end of pipe 50 being closed; the doser 65 is connected to the vapor supply tank 68 by pipe 64, port 60, passages 74 and 73, port 66 and pipe 67. As above described the movement of the movable members of the valve is a quarter of a revolution each time in two steps of one-eighth of a revolution each in the directions indicated by the arrows in Fig. 9. The first step of this movement makes the following changes: The doser 65 is disconnected from the vapor supply tank by passage 74 leaving port 60; bottle 1 is disconnected from the air pipe 70 by passage 77 leaving port 49, and it is now connected to the rough pump by passage 75 connecting ports 49 and 55; bottle 2, now containing a treated filament, disconnected from the circuit, is opened to the air by passages 77 and 76 connecting ports 48 and 69; bottle 3 is now disconnected from the fine pump by passage 71 leaving port 43, and during the pause between the two steps it is connected to the doser by the passage 72 connecting ports 43 and 61 and the vacuum in bottle 3 draws a charge of vapor from the doser, leaving the latter with a vacuum; bottle 4 is disconnected from the rough pump by passage 75 leaving the port 46 and is connected to the fine pump by passage 71 connecting ports 44 and 54. The second step of this movement disconnects bottle 3 from the doser, passage 72 being carried away from ports 43 and 61 and, as the bottle has been exhausted and charged with vapor, the filament therein is ready for treatment. This second step also brings passage 74 over port 61, again connecting the doser 65 with the vapor supply tank 68, and the vacuum in the doser helps to recharge it with vapor. The connections between bottles 4, 1 and 2 and the fine pump, the rough pump and the air respectively are not changed by the second step, as the passages 71, 75 and 77 are made wide enough to allow for this movement. The next movement of the valve connects bottle 1 with the fine pump, bottle 2 with the rough pump, bottle 3 with the air and bottle 4 with the doser during the pause between the two steps of the movement. At the end of the movement, the pipe leading to bottle 4 is closed at the valve, the filament in the bottle is undergoing treatment and the doser is again connected to the vapor supply tank. The next movement connects bottle 1 with the doser during the pause between the two steps of

the movement and then closes the pipe leading to this bottle at both of the valves; it also connects bottle 2 to the fine pump, bottle 3 to the rough pump and bottle 4 to the air and, at the end of the movement, connects the doser to the vapor supply tank. By the next movement the parts are brought back again to the position shown in Fig. 9, with bottle 1 connected to the air, bottle 2 to the doser during the pause between the two steps and closed at the valves at the end of the movement while the filament is being treated, bottle 3 to the fine pump, bottle 4 to the rough pump and the doser to the supply tank. It will thus be seen that by the movement of the valves each bottle is connected to the rough pump during the pause between two movements of the movable members of the valves, then to the fine pump during a like pause, then to the doser during a pause between the two steps of a single movement, during which it is charged with a dose of hydrocarbon vapor, is then cut off from the doser by the second step and remains cut off during the pause at the end of the movement while the filament is being treated, and is lastly opened to the air so that the treated filament may be removed and another inserted in its place and that at the end of each movement the doser is connected to the vapor supply tank. This cycle of operations is in progress on all the bottles simultaneously, each bottle being one step in the cycle in advance of the bottle next to it and the end bottle being one step in advance of the first one. The movement of the valves operates to transfer the rough pump each time to the next bottle which was previously open to the air, to transfer the fine pump to the next bottle previously connected to the rough pump, to connect the doser to the next bottle, that bottle having been exhausted by the fine pump, and then disconnect it to allow treating of the filament, to transfer the open air connection to the next bottle, that bottle now containing a treated filament, and to connect the doser to the vapor supply tank after it has given up its charge to one of the bottles and been disconnected from that bottle. Thus, at the end of each full movement of the valves, one of the bottles with a filament to be treated held in its clips is disconnected from the pumps and vapor supply after having been exhausted of air and charged with a dose of hydrocarbon vapor. At the end of the movement this filament is connected in circuit by the circuit-closer and the treatment begins, continuing until the resistance of the filament is made uniform throughout and the resistance decreased to the desired point when the circuit through the filament is automatically broken as will now be explained.

65 Referring to Fig. 10 of the drawings, 78, 79

and 80 represent three mains from a source of single phase alternating electric energy from which two currents of different potential can be derived simultaneously, main 79 being of lower potential than main 78 and main 80 being the negative return common to the other two mains. From main 78 a wire leads to the two coils 81 and 82 of a differential relay and from coil 81 a wire leads to a variable resistance 83 and back to main 79. From the other coil 82 of the relay a wire leads to one of the contacts 84 of the automatic circuit-breaker 91, the other contact of which is connected through an ammeter 85 and variable resistance 86 to one side of each of the filaments in the bottles 1, 2, 3 and 4 through one of the metallic strips 9 and 8 and one of the clips 7. On the other side, each filament is connected through its other clip 7 and metallic strips 8 and 9 to one contact of the pairs 35, 36, 37 and 38 adapted to be cross-connected by the contact 32 carried by the shaft 30. The other contacts of these pairs are connected together and to the negative main 80 as shown. 87 and 88 represent positive and negative mains from a source of electric energy from one of which a wire leads to a push-button switch 89 on the table, then through the coils of the electromagnet 18, returning to the other main through an indicator lamp 90. Thus the operator by pressing push-button 89 energizes magnets 18, releasing the operating mechanism and allowing shaft 10 to make one revolution and shaft 30 one quarter of a revolution. Mounted on the table is a double pole, spring-retracted switch 91 adapted to bridge contacts 84 with one pole and another pair of contacts 92 with the other and extending over the switch-blade is an arm 93 carried by the rod 27 which is pivoted eccentrically to shaft 10. Thus when shaft 10 makes one revolution, arm 93 throws switch 91 to the closed position where it is held by the spring-actuated latch 94. The circuit through one of the filaments however is not closed by the closing of the switch 91, as when the operating mechanism is at rest one of the teeth of wheel 28 is close to the position in which it engages the teeth of wheel 29 so that before switch 91 is closed, contact 32 is moved away from the pair of contacts which it has been bridging. After switch 91 has been closed by arm 93 the second tooth of wheel 28 actuates wheel 29 and contact 32 is carried to the position in which it bridges the next pair of contacts, and the connections are so arranged that this cuts into circuit the filament in the bottle which has just received a dose of vapor. The armature 95 of the differential relay carries a bridge piece adapted to cross-connect two contacts 96, completing a circuit from main 88 to one of the contacts 92

from the other of which a wire leads to the coil of an electromagnet 97 mounted in co-operative relation to the latch 94 of circuit-breaker 91 and back to main 87. When 5 the variable resistances 83 and 86 have been properly adjusted and circuit through one of the filaments is closed at the contacts 84 and one of the pairs of contacts 35, 36, 37, 38, the flow of current through the filament 10 will be comparatively small on account of its high resistance. This however does not affect the flow of current through the circuit of coil 81 of the relay which remains constant throughout the changes in the 15 resistance of the filament. Therefore when circuit is first completed through the filament, coil 81 of the relay will exert a stronger force on armature 95 than coil 82 and the armature will be held in the raised 20 position. As the resistance of the filament decreases, owing to the deposition of carbon thereon, the current through the filament and through coil 82 of the relay in series therewith increases until, when the desired 25 resistance is obtained, coil 82 balances coil 81. When this occurs, armature 95 drops by gravity, closing circuit through magnet 97, the contacts 92 being bridged by switch 91, and the magnet attracts its armature, 30 the latch 94. This releases switch 91 which is thrown to the open position by its spring opening the circuit through coil 82 and the treated filament and the circuit through magnet 97. Coil 81 remaining in circuit 35 again attracts armature 95, putting the parts in readiness for the treatment of the next filament.

In starting the machine, the pumps are started and the operator presses push-button 40 89 and operates the mechanism several times without putting filaments into the bottles to get the bottles in proper condition for operation. After each pressure of the button one bottle is open to the air, one charged with a 45 dose of vapor and closed at the valves, one connected to the fine pump and one connected to the rough pump and the doser after delivering its charge of vapor to the bottle is connected to the supply tank. The operator then inserts a filament in the clips of the bottle which is open to the air, places the cap in the closed position and presses 50 push-button 89. This energizes magnet 18 which attracts its armature and raises finger 22, thus releasing clutch-pin 13 and allowing shaft 10 to make one revolution and shaft 30, the circuit-closer and the movable valve-members one quarter of a revolution. Supposing the new filament was put in bottle 55 1, the action of the valves, as above explained, connects bottle 1 to the rough pump, bottle 2 to the air, charges bottle 3 with a dose of vapor and disconnects it, connects bottle 4 to the fine pump and the doser to the supply tank. The operator then puts a

filament in the clips of bottle 2, closes it and presses push-button 89. This operates the valves as before, connecting bottle 1 to the fine pump, bottle 2 to the rough pump, bottle 3 to the air, charges bottle 4 with vapor and then disconnects it and connects the doser to the supply tank. The operator then puts a filament in bottle 3 and again presses button 89, connecting bottle 1 to the doser, by the first step of the valve movement, from which it receives its charge of hydrocarbon vapor and disconnecting it at the valves by the second movement. This movement of the valves also connects bottle 2 to the fine pump, bottle 3 to the rough 75 pump, bottle 4 to the air and the doser to the supply tank. Shaft 10 in making the revolution which causes this operation of the valves draws rod 27 down, closing switch 91, and shaft 30 in making one quarter of a revolution moves contact 32 to the position in which, at the end of the movement, it bridges contacts 35. This closes a circuit from main 78 through coil 82, contacts 84, ammeter 85, rheostat 86, the filament in bottle 1, contacts 35 to main 80, and the filament is heated by the current passing through it thus precipitating carbon upon itself and increasing its current carrying capacity. The demagnetizing force exerted on armature 95 95 by coil 82 increases with the increase in the flow of current through the filament undergoing treatment, coil 82 being in series therewith, until it balances coil 81 thus allowing armature 95 to drop by gravity. 100 This bridges contacts 96, closing circuit through magnet 97 which attracts the latch 94 of switch 91, allowing the switch to be opened by its spring. Coil 81 which is in circuit throughout the operation of the machine immediately draws armature 95 up, leaving all parts of the machine in readiness for a repetition of the operation. While this is taking place, the operator puts a filament in bottle 4, and closes the bottle. He then presses push-button 89, connecting bottle 1, which now contains a treated filament, with the air, charging bottle 2 with a dose of vapor, closing it at the valves and connecting the filament therein in circuit and connecting bottle 3 to the fine pump, bottle 4 to the rough pump and the doser to the supply tank. The operator can then take the treated filament from bottle 1 and insert a new one in its place. The operation of the machine is continued in this manner, a filament being treated at each pressure of the push-button.

It will thus be seen that each of the parts is in action all the time and that in all four bottles some one operation is being conducted, and that the machine is automatic throughout, the only duties of the operator being to remove the treated filaments, put filaments to be treated in their places and 125 130

press push-button 89. The rheostats 83 and 86 can be so adjusted relatively to one another that the circuit through the filament will be opened when the exact resistance desired has been obtained. The operator is kept busy continually, as the time required for treating is no longer than that required to take out the treated filament and replace it with a new one and is in little or 10 no danger as only a single charge of vapor is in the machine at any time in its operation and little of this escapes into the room, the vapor supply tank being preferably located outside of the building and amply protected.

15 It must be understood that the invention is in no way limited to the machine shown in the drawings, as many changes can be made without departing from the spirit of the invention. The doser can be dispensed 20 with by connecting the bottles directly with the vapor supply tank through an opening of such size that the exact charge of vapor desired will pass into the bottles during the time between the opening and closing of the valves. In practice, however, I have found 25 it preferable to use the doser as a measure for the charges of vapor as it conduces toward greater uniformity in the size of the dose. Nor is it essential to use two pumps 30 for exhausting the treating bottles, as a single pump of larger capacity will be found sufficient. In this latter case one of the bottles could be readily dispensed with and in either case a single valve could be employed instead of two as shown. Other 35 changes in the parts would adapt the machine for operation with any number of bottles greater or less than that shown in the drawings. However, these changes and 40 others which can be made are all considered within the scope of my invention, which is not confined to treating machines for filaments but embraces any machine in which a series of receptacles or bulbs are exhausted 45 in sequence through automatic changes in the connections between the receptacles and the pump or pumps.

What I claim as new and desire to secure by Letters Patent of the United States, is,—
50 1. A filament treating machine having a receptacle in which the filament is treated, and automatic means for charging the receptacle with a predetermined amount of hydrocarbon for the treatment.

55 2. A filament treating machine having a plurality of treating receptacles, and automatic means for obtaining uniform charges of fluid for the treatment in the several treating receptacles successively.

60 3. A filament treating machine comprising a receptacle in which the filament is treated, a source of supply of fluid for the treatment, and automatic means for delivering to the receptacle a predetermined 65 charge of fluid from the source of supply.

4. A filament treating machine comprising a receptacle in which the filament is treated, a tank containing hydrocarbon vapor for the treatment, and automatic means permitting the flow of a predetermined 70 amount of vapor from the tank to the receptacle.

5. A filament treating machine comprising a plurality of receptacles in which filaments are treated, a source of supply of fluid for the treatment, and automatic means for charging the receptacles successively with uniform quantities of fluid from the source of supply. 75

6. A filament treating machine comprising a receptacle, means for supporting a filament therein, means for establishing electrical connection with a filament while in the receptacle, a source of supply of fluid distant from the receptacle, automatic means 80 permitting the passage of a definite amount of fluid from said source to the receptacle, and means for closing circuit to said electrical connecting means. 85

7. A treating machine comprising a receptacle, a source of supply of hydrocarbon distant from the receptacle, and automatic means for delivering to the receptacle uniform charges of hydrocarbon from the source of supply. 90

8. A treating machine comprising a receptacle, a source of fluid supply distant from the machine, means for exhausting the receptacle, and automatic means for admitting a definite amount of fluid to the receptacle from said distant source. 100

9. A filament treating machine comprising a receptacle in which the filament is treated, means for establishing electrical connection with a filament while in the receptacle, automatic means for supplying hydrocarbon to said receptacle, and means whereby circuit to said connecting means is closed after cutting off the supply of hydrocarbon. 105

10. A filament treating machine comprising a receptacle in which the filament is treated, means for establishing electrical connection with a filament while in the receptacle, a source of supply of hydrocarbon distant from the machine, means permitting the supply of hydrocarbon to the receptacle from said source, and means whereby cutting off the supply closes circuit to said connecting means. 110

11. A treating machine comprising a receptacle, a source of supply of fluid, a connection between the source of supply and receptacle, a valve in said connection, and automatic means for holding the valve in the open position for uniform periods. 115

12. A filament treating machine comprising a receptacle in which the filament is treated, means for supplying fluid at constant pressure, a vessel of definite size for 130

- measuring the fluid for the treatment, and means for connecting said vessel with the receptacle.
13. A treating machine comprising a receptacle, a source of supply of fluid, a measure, means for automatically connecting the measure with the source of supply, and means for automatically connecting the receptacle with the measure.
14. A filament treating machine comprising a plurality of receptacles in which filaments are treated, a source of supply of fluid for the treatment, a measure, and means for connecting the measure alternately with the source of supply and one of the receptacles.
15. A treating machine comprising a plurality of treating receptacles, a source of fluid supply, a measure, and means for connecting the measure alternately with the source of supply and with successive treating receptacles.
16. A filament treating machine comprising a receptacle in which the filament is treated, a source of fluid supply distant from the receptacle, a measure, and means for automatically connecting the measure with the source of supply and with the receptacle.
17. A filament treating machine comprising a plurality of receptacles in which filaments are treated, a source of fluid supply distant from the receptacles, a measure, and means for connecting the measure alternately with the source of supply and successive receptacles.
18. A filament treating machine comprising a receptacle in which the filament is treated, a source of supply of fluid for the treatment, a measure, and means for automatically connecting the measure with the source of supply and with the receptacle.
19. A filament treating machine comprising a plurality of receptacles in which filaments are treated, a source of supply of fluid for the treatment, a measure, and means for automatically connecting the measure alternately with the source of fluid supply and successive receptacles.
20. A filament treating machine comprising a receptacle, means for holding a filament therein, automatic means for delivering to the receptacle a predetermined charge of a fluid, and means for closing circuit through the filament.
21. A filament treating machine comprising a receptacle, means for holding a filament therein, automatic means for charging the receptacle with a predetermined quantity of a fluid, and means for automatically closing circuit through the filament.
22. A filament treating machine comprising a receptacle, means for holding a filament therein, a source of fluid supply distant from the receptacle, automatic means for delivering uniform charges of fluid to the receptacle from said source, and means for closing circuit through the filament.
23. A filament treating machine comprising a receptacle, means for holding a filament therein, a source of fluid supply distant from the receptacle, automatic means for charging the receptacle with a predetermined quantity of fluid from said source, and means for automatically closing circuit through the filament.
24. A filament treating machine having a plurality of receptacles, means for holding a filament in each receptacle, automatic means for admitting hydrocarbon to each receptacle, and means for automatically closing circuit through the several filaments successively.
25. A filament treating machine having a plurality of receptacles, means for holding a filament in each receptacle, automatic means for admitting a fluid to the receptacles, and means for automatically closing circuit through the several filaments successively.
26. A filament treating machine having a plurality of receptacles, means for holding a filament in each receptacle, means for admitting a fluid to the several receptacles successively, and means for automatically closing circuit through the several filaments successively.
27. A filament treating machine having a plurality of receptacles, means for holding a filament in each receptacle, means for charging each receptacle with a uniform quantity of a fluid, and means for automatically closing circuit through the several filaments successively.
28. A filament treating machine having a receptacle, means for holding a filament therein, a source of fluid supply, a measure, means for connecting the measure with the source of fluid supply and the receptacle, and an automatic circuit-closer for closing circuit through the filament.
29. A treating machine having a treating receptacle, a pump, and means for automatically and periodically connecting the pump with the receptacle.
30. A treating machine having a plurality of treating receptacles, a pump, and means for automatically connecting the pump with the several receptacles successively.
31. A treating machine comprising a treating receptacle, a plurality of pumps, and means for automatically and periodically connecting the pumps with the receptacle successively.
32. A treating machine comprising a plurality of treating receptacles, a plurality of pumps, and means for automatically connecting the pumps to the several receptacles successively, each pump being connected to each receptacle after another has been disconnected therefrom.

33. A treating machine comprising a treating receptacle, a pump, a source of fluid supply, automatic means for periodically connecting the pump with the receptacle, and means for automatically disconnecting the pump from and connecting the source of fluid supply to the receptacle. 70
34. A treating machine comprising a treating receptacle, a plurality of pumps, a source of fluid supply, and means for automatically and periodically connecting each of the several pumps and the source of fluid supply to the receptacle successively. 75
35. A treating machine comprising a plurality of treating receptacles, a pump, a source of fluid supply, and means for automatically connecting the pump and source of fluid supply to the receptacles successively, the source of fluid supply being connected to each receptacle after the pump has been disconnected from it. 80
36. A treating machine having a receptacle, a pump, a source of fluid supply, automatic means for connecting the pump to the receptacle and disconnecting it therefrom, and means for charging the receptacle with a predetermined quantity of fluid from the source of supply. 85
37. A treating machine comprising a receptacle, a tank containing the fluid for the treatment, a measure for the fluid, means for connecting the measure with the tank, means for exhausting the receptacle, and means for disconnecting the measure from the tank and connecting it to the receptacle, whereby the vacuum therein draws the charge of fluid into the receptacle. 90
38. A treating machine comprising a receptacle, a pump, a tank, a measure, means for connecting the measure with the tank and the pump with the receptacle, and means for disconnecting the pump from the receptacle and connecting the measure to the receptacle. 95
39. A filament treating machine comprising a treating receptacle, means for holding a filament therein, a source of fluid supply, a pump, and automatic means for successively connecting the receptacle to the pump, disconnecting it therefrom, connecting it to the source of fluid supply, disconnecting it therefrom, and closing circuit through the filament in the receptacle. 100
40. In a treating machine, a receptacle, means for supporting a filament therein, means for exhausting the same, and means for automatically placing the receptacle in communication with the air. 105
41. In a treating machine, a plurality of receptacles, means for supporting a filament in each receptacle, means for exhausting the receptacles successively, and automatic means for placing the receptacles in communication with the air successively. 110
42. In a treating machine, a receptacle, means for supporting a filament therein, automatic means for establishing electrical connection with a filament while held therein, and means controlled by the resistance of the filament for automatically opening a circuit to said connecting means. 115
43. In a filament treating machine, a receptacle, means for holding a filament therein, automatic means for establishing electrical connection with a filament while held therein, and means controlled by the resistance of the filament for automatically opening a circuit to said connecting means. 120
44. A filament treating machine having a receptacle in which the filament is held in a hydrocarbon vapor, means for automatically closing a circuit through the filament at predetermined intervals, and additional means whereby the circuit is automatically opened when the resistance of the filament reaches a predetermined value. 125
45. A filament treating machine comprising a plurality of receptacles in which filaments are treated, a vessel containing hydrocarbon for the treatment, and means for automatically establishing a connection between said vessel and successive receptacles. 130
46. A filament treating machine having a plurality of treating receptacles, means for holding a filament in each receptacle, means for carrying forward a succession of operations in each receptacle by which the filament therein is treated, and means whereby starting the operation in one receptacle causes the last operation to be performed in another receptacle. 135
47. A filament treating machine having a plurality of treating receptacles, means for holding a filament in each, and means for carrying forward a succession of operations in each receptacle to treat the filament therein, so arranged that the several receptacles are maintained at different stages of the cycle of operations. 140
48. A treating machine comprising a receptacle, a source of hydrocarbon vapor supply, a connection between the source of supply and receptacle, a valve in said connection, and means for heating the valve. 145
49. In a treating machine, a receptacle, a source of hydrocarbon supply, a connection between said source and the receptacle, a valve in said connection having movable and stationary members, a shaft carrying the movable valve member, means controlled by the operator for turning the shaft through a definite angle whereby the connection is opened or closed, and means for heating the valve. 150
50. A treating machine comprising a plurality of receptacles, a pump, a source of fluid supply, and means controlled by the operator for simultaneously connecting one receptacle to the pump, another to the source of fluid supply, and another to the air. 155
51. A filament treating machine having a receptacle, means for holding a filament 160

therein, a pump, a source of fluid supply, and automatic means for successively connecting the receptacle to the pump, disconnecting it therefrom, connecting it to the source of fluid supply, disconnecting it therefrom, closing circuit through the filament, opening the circuit, and opening the receptacle to the air.

52. In a treating machine, a receptacle, a valve having movable and stationary members, a shaft carrying the movable member, automatic means controlled by the operator for turning the shaft through a definite angle, and means whereby said movement opens or closes a connection to the receptacle.

53. A treating machine carrying a plurality of receptacles, a pump, a source of fluid supply, a valve having movable and stationary members, a shaft carrying the movable valve member, automatic means controlled by the operator for turning the shaft through a definite angle, and connections between the stationary valve members and the receptacles, the pump and the source of supply.

54. A treating machine comprising a plurality of receptacles, a pump, a source of fluid supply, valves having movable and stationary members, a shaft carrying the movable valve members, automatic means controlled by the operator for turning the shaft through a definite angle, and connections between the stationary valve members and the receptacles, the pump, the source of supply and the air.

55. A treating machine comprising a receptacle, a measure therefor, and means for supplying treating fluid to said measure at constant pressure.

56. A filament treating machine comprising a plurality of filament receptacles, a measure therefor, and means for supplying treating fluid to said measure at constant pressure.

57. In a lamp machine the combination with a receptacle and a plurality of devices for varying the pressure within said receptacle, of automatic means for connecting said receptacle to said devices in succession.

58. In a lamp making machine the combination with a plurality of receptacles and a device for varying the pressure within said receptacles, of automatic means for successively connecting said receptacles to said device.

59. In a lamp machine the combination with a receptacle and two devices connected to said receptacle to produce different pressures therein, of means automatically actuated at predetermined intervals to vary the connections between said receptacle and said devices and thereby vary the pressure within said receptacle.

60. In a lamp machine, the combination

with an exhaust pump, a connection whereby a receptacle may be connected to said pump, a valve for automatically controlling communication between said connection and said pump comprising two relatively movable members having flat surfaces in engagement and coöperating ports in said surfaces, a port in one of said members being in communication with said connection and another port in one of said members being in communication with said pump, and means for automatically moving said members intermittently and relatively to each other to connect and disconnect said pump and said connection for the receptacle.

61. In a lamp machine, the combination with a plurality of exhaust pumps, a connection whereby a receptacle may be connected to said pumps, and a valve for automatically controlling communication between said connection and said pumps comprising two flat relatively movable members in engagement with each other and having coöperating ports in their engaging faces, a port in one of said members being in communication with said connection and other ports in said member being in communication with said pumps, and means for moving said members relatively to each other to bring the ports in said members into and out of registry and thereby place said connection to the receptacle in communication with different pumps in different relative positions of said members.

62. In a lamp making machine, the combination of an exhaust pump, a plurality of connections whereby receptacles may be connected to said pump, a valve for controlling communication between said connections and said pump comprising two relatively movable members having flat surfaces in engagement and coöperating ports in said engaging surface, a port in one of said members being connected to said pump and other ports in one of said members communicating with said connections, and driving mechanism for automatically moving said members relatively to each other to bring the ports in said members into and out of registry and thereby bring said pump into and out of communication with the connections to the receptacles one after the other.

63. In a lamp machine, the combination of a receptacle, a plurality of exhaust pumps, a controlling valve between said receptacle and said pumps comprising a flat seat containing a port in communication with said receptacle and other ports in communication with said pumps, a flat valve member movably mounted on said seat and provided with ports to register with the ports in said seat and thereby vary the connections of the receptacle to said pumps as said member is moved over said seat, and means for automatically moving said mem-

ber to bring its ports into and out of registry with the ports in the valve seat.

64. In a lamp machine, the combination with an exhaust pump, a plurality of connections whereby receptacles may be connected to said pump, a controlling valve between said connections and said pump comprising members mounted to rotate relatively to each other about a common axis, 10 said members having flat surfaces in engagement and coöperating ports in said surfaces, a port in one of said members being in communication with said pump and other ports in one of said members communicating with said connections, and actuating means for intermittently and automatically rotating said members relatively to each other to bring said ports in said members into and out of registry to control the communication between said connections for the 15 receptacles in said pump.

65. In a lamp machine, the combination with a plurality of exhaust pumps, a plu-

rality of connections whereby receptacles may be connected to said pumps, a valve for 25 automatically controlling communication between said connections and said pumps comprising relatively movable flat members in engagement with each other and having a plurality of coöperating ports in their 30 engaging surfaces, ports in one of said members being in communication with said pumps and other ports in one of said members being in communication with said connections, and actuating means for automatically 35 moving said members into different relative positions and thereby bringing different ports into registry to vary the relation of the connections for the receptacles to said pumps.

In witness whereof, I have hereunto set my hand this 15th day of October, 1903.

JOHN W. HOWELL.
